WEFT DETECTING MECHANISM FOR DROP BOX LOOMS

Oscar V. Payne, Leicester, Mass., assignor to Crompton & Knowles Loom Works, Worcester, Mass., a corporation of Massachusetts

Application May 31, 1932, Serial No. 614,393
Renewed January 3, 1935

3 Claims. (Cl. 139—233)

This invention relates to devices for detecting substantial exhaustion of weft in a shuttle which is active or about to become active in a multi-shuttle drop box loom.

5 My invention is particularly designed for use with loom stopping mechanism but may be adapted to initiate weft replenishment.

It is the general object of my invention to provide improved and simplified means for giving 10 an indication of substantial weft exhaustion for the shuttle which is active or about to become active, and for determining such shuttle without reference to the pattern mechanism of the loom.

To the accomplishment of this object in the 15 preferred form, I provide a separate detector for each shuttle, permanently associated with its assigned shuttle box. I cause all of said detectors to be moved to detecting position just prior to the picking of a shuttle and after the shifting of the 20 boxes is largely completed.

I also provide means by which one detector only completes an indication for any one position of the shuttle boxes, which indication is for the 25 shuttle in active position or about to become active.

My invention further relates to arrangements and combinations of parts which will be herein-after described and more particularly pointed out in the appended claims.

30 A preferred form of the invention is shown in the drawings, in which

Fig. 1 is a front elevation, partly in section of portions of a loom having my improved detecting mechanism applied thereto;

35 Fig. 2 is a detail sectional elevation, taken along the line 2—2 in Fig. 1;

Fig. 3 is a sectional end elevation of the parts shown in Fig. 1, and taken along the line 3—3 in Fig. 1;

40 Fig. 4 is a detail sectional plan view, taken along the line 4—4 in Fig. 3;

Fig. 5 is a plan view of certain parts shown in Fig. 1, and

45 Figs. 6, 7, 8 and 9 are diagrammatic plan views, illustrating the method of operation of the invention.

50 Referring to the drawings, I have shown portions of a drop box loom including a loom side 10 and a lay 11 mounted on swords 12 and swinging on the usual rock shaft 13. The lay 11 is provided

with a lay end 14, fixed thereto and having vertical guide-ways 15 for a set of drop boxes 20, indicated in Fig. 3 as having four compartments to receive four superposed shuttles S. The upper shuttle S is indicated as substantially exhausted and the other shuttles as each having a substantial amount of weft thereon.

The drop boxes 20 are mounted on the upper end of a lifter rod 22, guided in a bearing 23 on a bracket or stand 24, secured to the end of the rock shaft 13. The lifter rod and drop boxes are moved vertically by a chain 25 controlled by suitable pattern and box-shifting mechanism (not shown).

The parts thus far described are or may be of 15 the usual commercial type and in themselves form no part of my present invention, for the purposes of which I provide a stand 30 (Figs. 1 and 3) firmly secured by bolts 31 and 32 to upper 20 and lower portions of the drop box structure 20.

The stand 30 is provided with four laterally projecting arms or supports 33, on each of which a weft detecting device is mounted. This detecting device comprises a base or holder 35 adapted to be secured to one of the arms or supports 33 previously described, and a slide 36 mounted in suitable guide-ways in the base 35. A detector 37 is pivoted at 38 on each slide 36 and is limited in movement relative thereto in one direction by a stop pin 39 (Fig. 5). A spring 40 yieldingly holds the detector 37 in the position shown in Figs. 5, 6 and 7.

When the detector 37 engages a weft carrier or bobbin B having a sufficient supply of weft thereon, the detector is held thereby from side- 35 wise or slipping movement and is pushed directly forward, moving the slide 36 along its guide-ways in the base 35 but without any turning movement of the detector 37. If, however, the supply of weft on the weft carrier B is substantially exhausted, the detector 37 will slide along the butt of the weft carrier, moving to the position indicated in Fig. 9. This causes a forwardly extending portion 41 of the detector to swing outward and engage a contact plate 42, by which engagement a circuit through suitable loom-stopping mechanism (not shown) is completed and the loom is thus brought to rest.

Any suitable form of electrically controlled loom-stopping mechanism may be utilized, as 50

this mechanism and also the weft detector in themselves form no part of my present invention. For a more complete disclosure of the details and operation of the weft detector, reference is made to my prior Pat. 1,738,198, issued Dec. 3, 1929.

I have made special provision for normally maintaining the weft detectors in a forward or inoperative position except for a very brief period just before the picking of a shuttle. For this purpose I provide each slide 36 with an up-turned front end portion 44, positioned for engagement by studs 45 projecting laterally from an upright bar 46 (Fig. 1) mounted in the upper end of a supporting bar 47.

The hub 48 of the arm 47 is fixed to the upper end of an actuating shaft 50 shown as being square or otherwise non-circular in section in its lower portion. The upper or cylindrical portion 20 of the rod 50 is mounted in a bearing 51 on an arm 52 formed as an extension of the feeler stand or support 30 which is movable with the drop boxes. The rod 50 extends downward through a square opening in the hub 60 (Fig. 2) of an actuating arm 61 (Fig. 1) provided with a cam roll 62. The arm 61 is rotatably mounted in a bearing 64 at the outer end of an arm 65, bolted to a downwardly offset member 66, which in turn is bolted to the under side of the lay end 14. 25 Collars 67 (Fig. 2) prevent upward or downward displacement of the hub 60.

With this construction, it will be evident that an operative connection is provided between the arm 61 and the arm 47 in every vertical position 30 of the rod 50.

The cam roll 62 is positioned adjacent a cam block 70, bolted to a bracket 71 on the loom side 10, and having a raised portion 72 and a depressed portion 73. As the lay moves rearward, the shaft 40 50, arm 61 and roll 62 will also move rearward and the cam roll 62 will be moved to the high portion 72 of the cam block 70, thus moving the arm 47 from the position shown in Fig. 6 and in dotted lines in Fig. 5 to the position shown in Fig. 7 and in full lines in Fig. 5, in which latter position the 45 studs 45 engage the up-turned ends 44 of the slides 36 and draw all of the weft detectors 37 forward to inoperative position and entirely out of the associated shuttles.

50 When the lay moves forward and the cam roll 62 reaches the depressed cam portion 73, a spring-actuated link 75 swings the arm 61 and arm 47 and associated parts to the position indicated in Fig. 6, thus restoring the weft detectors to the 55 control of the separate detector springs 40. Each detector is then moved rearward by its separate spring into the associated shuttle box and engages the weft on the weft carrier or bobbin B therein.

60 If the weft in any one of the shuttles, such as the upper shuttle S, is substantially exhausted, the corresponding detector 37 will swing about its pivot 38, as indicated in Fig. 9. If this particular shuttle is substantially in active position, the swinging detector will engage the contact plate 42 and complete the loom stopping circuit.

65 If on the other hand the swinging detector is associated with a shuttle substantially out of active position, the detector will be too high or too low to engage the contact plate 42 and no indication of substantial weft exhaustion will be given.

70 Under certain weaving conditions, the shifting of the shuttle boxes is not completed until after 75 the lay has passed front center. It is obviously

necessary to prevent release and operation of the weft detectors until the movement of the boxes is so far completed that the wrong detector cannot engage the contact plate 42.

For this reason, I provide an auxiliary cam block 80 (Fig. 1) mounted on a bell crank 81 pivoted at 82 on a downwardly projecting portion 83 of the fixed bracket 71 previously described. The bell crank 81 is connected by a link 84 to one end of a lever 85 (Fig. 3) pivoted at 86 and having a cam roll 87 positioned for engagement by a double cam 88 mounted on the usual cam or bottom shaft 90 of the loom.

When the roll 87 is engaged and pushed downward by a raised portion of the cam 88, the auxiliary cam block 80 will be moved outward to the position shown in Figs. 1 and 8, in which position the cam roll 62 is prevented from engaging the depressed portion 73 of the cam block 70. The weft detectors 37 will thus be held in forward 20 position until the cam roll 87 enters a depressed portion of the double cam 88.

In this way it is possible to hold the weft detectors inoperative for any desired portion of the loom cycle. In actual operation, the feelers 25 under certain conditions are thus held inoperative until the lay has reached or even passed front center.

With my auxiliary cam block, the detectors may be rendered operative for any desired portion of the loom cycle, it being only necessary that sufficient time for an indication be provided before the roll 62 (Fig. 6) reaches the rise on the cam block 70, which point is reached on the rearward stroke substantially at top center and at the time 35 when picking occurs.

While the final limit of indication is thus fixed, the beginning of indication may be varied by changing the outline or setting of the cam 88. The beginning of indication is preferably so selected that the drop box movement is largely completed before the detectors are released. Otherwise a detector not associated with a shuttle which is active or about to become active may engage the contact plate 42.

Having thus described my invention and the advantages thereof, I do not wish to be limited to the details herein disclosed, otherwise than as set forth in the claims, but what I claim is:—

1. In a loom having a plurality of drop boxes, 50 in combination, a separate side-slipping and normally inoperative weft detector permanently associated with each drop box, means to simultaneously withdraw all of said weft detectors from operative position for a major portion of the loom 55 cycle, said means comprising a fixed cam block having raised and depressed portions and a cooperating cam follower mounted to swing with the lay and connected to withdraw said weft detectors, and additional means to vary the duration 60 of the inoperative period for said detectors.

2. In a loom having a plurality of drop boxes, 65 in combination, a separate side-slipping and normally inoperative weft detector permanently associated with each drop box, means to simultaneously withdraw all of said weft detectors from operative position for a major portion of the loom cycle, said means comprising a fixed cam block having raised and depressed portions and a cooperating cam follower mounted to swing with the 70 lay and connected to withdraw said weft detectors, and additional means to vary the duration of the inoperative period for said detectors, said additional means comprising a member 75 mounted adjacent said cam block and movable to

temporarily prevent said cam follower from moving into the depressed portion of said cam block, and automatic means to move said member.

3. In a loom having a plurality of drop boxes, in combination, a separate side-slipping and normally inoperative weft detector permanently associated with each drop box, means to simultaneously withdraw all of said weft detectors from operative position for a major portion of the loom cycle, said means comprising a fixed cam block having raised and depressed portions and a coop-

erating cam follower mounted to swing with the lay and connected to withdraw said weft detectors, and additional means to vary the duration of the inoperative period for said detectors, said additional means comprising a member mounted adjacent said cam block and movable to temporarily prevent said cam follower from moving into the depressed portion of said cam block, and a constantly rotated cam connected to move said member.
